Primary Examiner — Lucy Lieberman

(74) Attorney, Agent, or Firm — Wood, Herron & Evans,
LLP(57) **CLAIM**

The ornamental design for a watch face, as shown and described.

DESCRIPTION

FIG. 1 is a perspective view of a watch face showing my new design; and,

FIG. 2 is a top plan view thereof.

The wristwatch that is shown in broken lines in the drawings does not form part of the claimed design.
